The ornamental design for a control device for nebulizer, as shown and described.

DESCRIPTION

FIG. 1 is a top, front, right side perspective view of a control device for nebulizer showing our design;

FIG. 2 is a bottom, rear, left side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings depict portions of the control device for nebulizer that form no part of the claimed design.
